DUPLICATING ROLL SPINDLE

Samuel Offer, Chicago, Ill., assignor to U. S.
Duplicator Company, Chicago, Ill., a corpora-
tion of Illinois

Application October 23, 1933, Serial No. 694,698

6 Claims. (Cl. 242—74)

The spindle of the present invention is designed primarily for use on duplicating machines which utilize a gelatine band for reproducing the imprinted copy; and in rolls of this character it is 5 desirable to provide means for attaching the end of the gelatine band to the roll in such a way that the attachment of the band to the spindle can be readily made without difficult manipulation, and so that after the band has been un- 10 wound from the spindle it will automatically release itself from engagement with the spindle without the necessity for special manipulation.

Spindles of the character here involved are 15 constructed to serve either as the winding spindle or as the delivering spindle, and the present invention is directed primarily to the combined features involved in the formation of the spindle itself and in the attaching end of the band, which are so correlated as to readily and conveniently 20 engage with one another when it is desired to apply the band to the spindle and readily disengage when release of the parts is required.

Further objects and details of the invention 25 will appear from the description thereof in conjunction with the accompanying drawings, wherein,—

Figure 1 is a side elevation of a duplicating machine of conventional form embodying the spindles of the present invention;

30 Fig. 2 is a cross sectional view taken on line 2—2 of Fig. 1, particularly showing the engagement of the chuck end of the spindle with the winding handle;

Fig. 3 is an enlarged view taken on line 3—3 of 35 Fig. 2, showing the winding chuck which coacts with the end of the spindle in winding the same;

Fig. 4 is a detail showing the acting inner face of the chuck member;

Fig. 5 is an enlarged detail taken on line 5—5 40 of Fig. 2, showing the means for journalling the opposite end of the spindle;

Fig. 6 is a perspective view of the spindle with the attaching end of the gelatine band secured thereto.

45 Fig. 7 is a similar enlarged view showing the spindle without the band in place; and

Figs. 8, 9 and 10 are cross sectional views taken on line 8 in Fig. 6, showing the band in various positions of adjustment with relation to the spindle.

The spindle 20 of the present invention may serve either as the winding spindle or the delivering spindle, and as shown two of such spindles are employed in a duplicating machine, which 50 comprises a front side plate 21 and a rear side

plate 22 which are suitably connected by tie rods 23, or in any other conventional manner.

The machine has a bed plate 24 over which the gelatine band 25 is stretched in the usual manner, the spindles operating to draw the band progressively across the surface of the bed in order to expose the portion of the band required to take the impression.

The gelatine band terminates at each end in a tapering section 26 which is preferably formed 10 of suitable fabric, and each of these tapering end sections has inserted therein an attaching strip 27 which is held in place by reversely turning the fabric to furnish a loop 28 which surrounds the strip. The strip is flattened on its inner face 29 15 and circumferentially rounded on its upper face 30, the configuration in cross section being that of a cord or section of the cylindrical spindle 20, and the strip with the surrounding fabric being 20 of a size and shape to fit within the flat bottomed recess 31 formed on one side in the center of the spindle and bounded at its ends by flat end walls 32. The insertion of the strip 27 into the loop in 25 the end of the fabric 26 distends the fabric and affords a stiffening or reinforcement for the end 25 of the strip, so that when the reinforced end is positioned in place within the slot in the spindle, a firm continuous cylindrical surface will be afforded for the winding of the gelatine strip.

In order to hold the parts in place, a stud 30 33 is provided in the center of the slot which enters an aperture 34 extending through the looped fabric and through the strip 27, said aperture being preferably afforded by the metallic 35 walls of an eyelet 35, the ends of which are flanged or upset to overlie the fabric and furnish a suitable binding therefor. The parts are so arranged as to fit snugly together when positioned as in Fig. 8, which affords a firm winding 40 surface for the turns of the gelatine band, as indicated in Fig. 9; and Fig. 10 illustrates the manner in which the end of the strip will release itself from engagement with the stud 33 when the band is being wound up on the companion 45 spindle.

The body of the spindle is preferably formed of wood and is headed at each end by a cap 36, to the outer face of which is secured an outstanding Z-shaped chuck-engaging member 27, the 50 ends 38 of which extend oppositely to one another and in angular relation to the body of the member. A journal stud 39 projects outwardly from the center of the chuck-engaging member. The chuck-engaging member thus formed is designed 55

to coat with a chuck head 40 on the inner end of a winding shaft 41 which is journalled within a journal plate 42 on the near side of the machine, the same arrangement being duplicated 5 at each end of the machine. Handles 43 are provided for winding the spindles to advance the gelatine band in either direction, as occasion may require, and suitable dog and ratchet mechanism 44 is also employed, as is customary in devices 10 of this character. The chuck head 40 is provided in its face with a cross groove 45, in the center of which is a circular bore or recess 46 to receive the journal stud 39. The side faces of the chuck head are squared to fit within the 15 extensions 38 (see Fig. 3).

The opposite end of the spindle has the journal stud 39 journalled within a notch 47 within a fixed plate 48 secured to the inner face of the side wall 22, and the fixed 20 notched plate co-operates with a lever 49 pivoted on a pintle 50. A spring 51 secured to the short arm 52 of the lever serves to hold the long arm 53 elevated in position to hold the journal stud within the notch 47, but the arrangement of the 25 parts permits the journal stud to be withdrawn by depressing the long arm of the lever, as indicated in dotted lines in Fig. 5. The under edge 54 of the plate 48 is convexly rounded and merges into the notch 47 in such a way as to 30 afford a throat for the entrance of the journal stud, so that when it is desired to mount the spindle in place, its chuck-engaging end will first be inserted into position while the spindle is standing obliquely with respect to the walls 35 of the machine, after which the opposite end of the spindle will be swung laterally to permit the journal stud to slip into place and journal itself between the fixed journal plate and the spring-pressed lever.

40 In using the machine, an empty spindle will be positioned in place to serve as the winding spindle, while a loaded spindle carrying the wound up gelatine band will be similarly mounted in position to serve as the delivering spindle. The 45 outer or free end of the band will be drawn forward and hooked on to the stud of the winding spindle. This manipulation is easily accomplished by one hand of the operator, and without close attention, which is an important feature 50 of advantage in a device of this character, since the position of the spindles beneath the bed of the machine is such that close or accurate manipulation is difficult, and provision must be made to permit the parts to be easily assembled 55 under such adverse conditions.

The present arrangement is one which permits the stiff reinforced and distended end of the band to be easily fitted into place within the recess in the wall of the winding spindle and to be hooked on to the upstanding stud, after which the first turn of the winding spindle in the proper direction will cause the fabric to wind over the firm uniformly cylindrical surface thus presented, so that thereafter the winding will proceed uniformly and without difficulty as the sections of the gelatine band are progressively exposed upon the bed of the machine for use. When the terminus of the band is reached, the band will automatically release itself from the delivering spindle, after which it is completely wound up on the winding spindle for removal from the machine. Removal of the spindles is easily effected, since a moderate tension exerted on the journalled end of the spindle will cause the journal 75

stud to release itself from the spring-pressed journal mounting.

The spindles being interchangeable end for end, either spindle may serve as a winding or delivering spindle, and the invention as a whole 5 is designed with a view of facilitating the operations involved and of affording a firm and truly cylindrical winding surface, so that the winding will be smooth and even and properly centered.

Although the invention has been particularly 10 described as a winding spindle applicable for use in connection with duplicating machines, it is obvious that it might be used in connection with other types of machines or appliances in which it is desirable to afford a detachable connection 15 between the spindle or the strip or sheet wound thereupon.

I claim:

1. In mechanism of the class described, the combination of a spindle presenting a winding 20 surface of uniform curvature at its ends and from end to end save for the formation of a recess in the medial region, and a band adapted to be wound upon the spindle and having secured to its attaching end a stiff section of reinforcing material configured to fill the recess and afford a uniformly curved winding surface in continuation of the surface afforded by the spindle.

2. In mechanism of the class described, the 30 combination of a spindle presenting a winding surface of uniform curvature at its ends and from end to end save for the formation of a recess, a band adapted to be wound upon the 35 spindle and having secured to its attaching end a stiff section of reinforcing material configured to fill the recess and afford a uniformly curved winding surface in continuation of the surface afforded by the spindle, and an attaching stud upstanding from the recessed portion of the 40 spindle, the reinforced attaching end of the band being provided with an aperture adapted to maintain engagement with the stud when the band is wound around the spindle and to freely 45 release therefrom when the band is completely 50 unwound.

3. In mechanism of the class described, the combination of a spindle presenting a winding 55 surface of uniform curvature at its ends and from end to end save for the formation of a 60 recess, a band adapted to be wound upon the spindle and having secured to its attaching end a stiff section of reinforcing material configured to fill the recess when presented from either side of the recess and afford a uniformly curved 65 winding surface in continuation of the surface afforded by the spindle, and the spindle being provided at each of its ends with a chuck-engaging member 70 configured to engage with a winding chuck, and a journal spindle outstanding from the chuck-engaging member and adapted to co-act with a journal bearing to permit either end of the spindle to receive a driving connection.

4. In mechanism of the class described, the combination of a spindle presenting a winding 75 surface of uniform curvature at its ends and from end to end save for the formation of a recess, a band adapted to be wound upon the 80 spindle and having secured to its attaching end a stiff section of reinforcing material configured to fill the recess when presented from either side of the recess and afford a uniformly curved winding 85 surface in continuation of the surface afford- 90

ed by the spindle, and an attaching stud up-
standing from the recessed portion of the
spindle, the reinforced attaching end of the band
being provided with an aperture adapted to en-
gage with the stud when the band is wound
5 around the spindle and to freely release there-
from when the band is completely unwound, and
the spindle being provided at each of its ends
with a chuck-engaging member configured to
10 engage with a winding chuck, and a journal
spindle outstanding from the chuck-engaging
member and adapted to coact with a journal
bearing to permit either end of the spindle to
receive a driving connection.

15 5. In mechanism of the class described, the
combination of an elongated cylindrical spindle
having in its center portion a flat bottomed
recess, a stud upstanding from the bottom of
20 said recess, a band having an attaching end of
reduced width, a reinforcing strip secured to the
end of the band and configured to afford a flat
under surface for contact with the flat bottom
25 of the recess, and having a curved outer surface
conformable to the curvature of the spindle sur-
face and constituting a continuation thereof, the
parts being adapted when assembled to afford

a firm uniformly curved winding surface, and
the reinforcing strip being provided with an
aperture adapted to engage with the stud when
the band is wound around the spindle and to
freely release therefrom when the band is com-
5 pletely unwound.

6. In mechanism of the class described, the
combination of an elongated cylindrical spindle
having in its center portion a flat bottomed
recess, a stud upstanding from the bottom of 10
said recess, a band having an attaching end of
reduced width, and having the end portion there-
of lapped to afford a loop, a stiff reinforcing strip
entered through said loop and configured to have
15 a flat under surface for contact with the flat bottom
of the recess, and having a curved outer surface
conformable to the curvature of the spindle sur-
face and constituting a continuation thereof, the
parts being adapted when assembled to afford
20 a firm uniformly curved winding sur-
face, and the reinforcing strip being provided
with an aperture adapted to detachably engage
with the stud, the walls of said aperture being
reinforced by an eyelet upset at its ends to clamp
25 the margins of the loop adjacent the aperture.
